UNITED STATES PATENT OFFICE

92,696

DESIGN FOR A SHOE

Benjamin Benjamin, Brooklyn, N. Y.

Application May 5, 1934, Serial No. 51,697

Term of patent 3½ years

To all whom it may concern:

Be it known that I, BENJAMIN BENJAMIN, a citizen of the United States, residing in 134 Noll Street, Borough of Brooklyn, county of Kings, city and State of New York, have invented a new, original, and ornamental Design for Shoes, of which the following is a specification, reference being had to the accompanying drawing, forming part thereof.

Fig. 1 is a side elevation of a shoe showing my new design; and

Fig. 2 is a view of the opposite side of the shoe as disclosed in Fig. 1.

I claim:

The ornamental design for a shoe, as shown. In testimony whereof, I have affixed my signature in the Borough of Brooklyn, county of Kings, city and State of New York, this twenty-seventh day of April 1934.

BENJAMIN BENJAMIN.
